UNITED STATES PATENT OFFICE.

JEROME REDDING, OF MALDEN, MASSACHUSETTS, ASSIGNOR TO FRANCIS H. LORD,
TRUSTEE, OF SOUTH WEYMOUTH, MASSACHUSETTS.

TELEPHONE-TRANSMITTER.

1,095,354.

Specification of Letters Patent.

Patented May 5, 1914.

Application filed June 17, 1910. Serial No. 567,368.

To all whom it may concern:

Be it known that I, JEROME REDDING, a citizen of the United States, residing at Malden, county of Middlesex, and State of Massachusetts, have invented an Improvement in Telephone-Transmitters, of which the following description, in connection with the accompanying drawing, is a specification, like characters on the drawing representing like parts.

This invention relates to telephone transmitters and has for its object to provide a novel transmitter which is constructed so that it can be successfully used with currents of a comparatively high voltage.

The telephone transmitter now in universal use is designed to be used with a low voltage current and is so constructed that if the voltage increases beyond a certain amount snapping or hissing noises are produced which interfere materially with the transmission of sound. A current of low voltage can only be used on a comparatively short line because if the length of the line is increased beyond certain limits the resistance of the line will be such as to preclude the use of a low voltage. Accordingly for long distance lines it has become the practice to use an induction coil or transformer in connection with the telephone for the purpose of converting the low voltage local current connected to the transmitter into a current of higher voltage which is used on the line. The use of an induction coil in this connection has some disadvantages however, partly due to the hysteresis developed in the induction coil and partly due to the fact that the current induced by the induction coil is an alternating current which is not as desirable in many ways for transmitting sound as a direct current is.

My invention aims to provide a novel transmitter which can be used with a direct current of high voltage so that the transmitter may be connected directly to a long distance line without the use of an induction coil or transformer and will not be affected in any disadvantageous way by the employment of a direct current of sufficiently high voltage to carry the full length of the long distance line.

In the drawings wherein I have illustrated one embodiment of my invention, Figure 1 is a side view of a telephone transmitter embodying the invention; Fig. 2 is a sec-

tion on the line $x-x$, Fig. 1; Fig. 3 shows the back side of the transmitter with the cover 40 removed; Fig. 4 is a section transversely through a portion of the telephone transmitter on the line $a-a$, Fig. 2; Fig. 5 is a detail sectional view of one of the cells or variable resistance elements.

My improved telephone transmitter comprises a plurality of separate cells or variable resistance units which are connected in series with each other and with the line and all of which are so situated relative to the main sound-transmitting diaphragm of the instrument that when said diaphragm vibrates, the resistance of all the resistance units will be varied simultaneously. Where the resistance units are connected in series the total resistance in the line is the sum total of the resistance of the individual units which are connected in series, and as the resistance of all the units varies simultaneously a much greater total variation in the resistance of the line is secured than is possible with a single cell or resistance unit. In this way it is possible to use a current of a high voltage without any deleterious effects. The individual cells or resistance units are confined within a suitable casing 3 which supports the main sound-transmitting diaphragm 4, the front 5 of the casing having the usual opening for the transmission of the sound vibrations, and preferably carrying a mouth-piece 6, as usual. The main diaphragm 4 may be secured in the casing in any suitable way without departing from the invention. I have herein shown the edge thereof as clamped between the edge of the front 5 and the main body of the casing. The front 5 of the casing is shown as removable and is secured in place by the clamping bolts 9. I have shown the edge of the main diaphragm 4 as confined between two gaskets 10 of rubber or other similar insulating material which are clamped in place by said clamping bolts.

The separate resistance units are supported by a plate 11 of insulating material which is secured to and sustained by the casing 3. These resistance units are in some respects similar to the variable resistance of an ordinary microphone in that they comprise cells which are filled with finely-granulated and preferably high resistance carbon or other suitable material 17 through which the current passes. One of these cells is shown in

enlarged section in Fig. 5 and it comprises a body 12 of insulating material within which is situated a carbon plate or terminal 13 which has a brass or other metallic plate 14 secured to the back side thereof. The plate 14 is provided with the hub 15 which extends through the end of the cell and from which extends a stem 16 of good conducting material by which the cell is supported in the plate 11. The cavity in the body 12 is filled with granulated carbon or similar material 17, and preferably some high resistance carbon will be used, such, for instance, as would be obtained by finely pulverizing the carbon. Said cavity is closed by a flexible diaphragm 18 of conducting material which is clamped to the body by a clamping ring 19, said ring preferably being hexagonal or flat-sided so as to permit it to be readily turned. I prefer to make the flexible diaphragms 18 of pure silver as I have found that when made in this way the diaphragms are more sensitive and will not become oxidized by the current. The flexible diaphragm 18 of each cell is arranged to be vibrated by the vibrations of the sound-receiving diaphragm 4, so that the resistance of the cells will vary in accordance with the sound vibrations to be transmitted. There are various ways in which this can be accomplished, but I find good results can be secured by mechanically connecting each diaphragm 18 to the main diaphragm 4.

As herein shown each cell diaphragm has extending therefrom a screw 29 on which is screw-threaded two clamping nuts 20 and 21 between which the diaphragm 4 is clamped, thus making a rigid connection between said diaphragm 4 and each cell diaphragm. Any other suitable arrangement by which the vibrations of the diaphragm 4 will be transmitted to the cell diaphragms may be adapted, however, without departing from the invention.

A sufficient number of the resistance units are connected in series so that the sum total of the resistance of all such units bears the correct relation to the resistance of the line and the voltage of the current to be used. Under ordinary circumstances I would propose to connect all the cells in series, as shown in the drawings, but under some circumstances it may be desirable to divide the cells into two or more groups and connect the cells of each group in series while the groups are connected in multiple arc. The cells are each insulated from the casing and this may be done in various ways. If the diaphragm 4 is of mica or other insulating material, said diaphragm will act as an insulator, but if said diaphragm is of metal or any other conducting material then I may make the nuts 20 and 21 of insulating material.

The electrical connection between the various resistance units may be made in any suitable way, and as herein shown the clamping ring 19 of each cell is electrically connected with the stem 16 of the next cell by means of a wire 22, as shown in Fig. 3. These wires 22 may be secured to the clamping nuts 19 and stems 16 in any suitable way. I have herein shown each wire as soldered or otherwise permanently connected to one clamping nut 19 and as passing through an aperture 23 in the plate 11 and as secured to the stem 16 of the next cell by means of two clamping nuts 24 thereon. The various resistance cells are insulated from each other and this may conveniently be done by inclosing each clamping nut 19 in an envelop 25 of insulating material. The wires 26 and 27 of the line are shown as leading to and connected with two terminals or binding posts 48, 49, and the binding post 49 is connected by a wire 30 with a clamping nut 19 of the first cell of the series, while the binding post 48 is connected by a wire 31 with the stem 16 of the last cell of the series. With such a construction it will be seen that whenever the main diaphragm 4 vibrates the vibrations will be transmitted to all the cell diaphragms 18, and thus the resistance in all the cells will vary simultaneously. Since the resistance between the terminals 48 and 49 is the sum total of the resistance of all the cells connected in series, it will be apparent that the amount of variation in the resistance of the line due to the vibration of the diaphragm 4 will be the sum total of the variation in the resistance of all such cells. With such an arrangement it is possible to use a current of a comparatively high voltage without interfering in any way with the proper use of the instrument. This enables me to connect the instrument directly to a long distance telephone line without the use of induction coils and yet to use a current of sufficiently high voltage to overcome the resistance of the line without any such loss in current strength as will interfere with the proper use of the instrument.

In order to get the best results it is desirable that the diaphragm 4 should not be subjected to any internal strains due to its connection with the individual cells. It will readily be seen that if all the cells 12 were rigidly sustained by the plate 11 and any one or more cells should be out of proper alinement, the diaphragm 4 would be subjected to internal strains which would interfere with the transmission of delicate sounds. In order to prevent this I have provided a novel way of supporting the individual cells so that each will be yieldingly sustained and can assume such a position relative to the main diaphragm as to prevent the presence of any objectionable internal strains therein. While there are vari-

ous ways of yieldingly supporting the individual cells to secure this object, I have shown a construction wherein the stem of each cell passes loosely through a sleeve or bushing 35 sustained by the plate 11 and is centered and properly positioned by two springs 36, 37 that encircle the stem and are situated at either end of the bushing, one spring 37 being confined between said bushing and the cell, and the other spring being confined between said bushing and the nuts 24. By properly adjusting the clamping nuts 24, it is possible to give the two springs 36, 37 the proper tension so that each cell 15 will be supported in such a manner that it will not subject the diaphragm 4 to any strain because of its position.

The casing 3 may be made in a variety of ways without departing from the invention. I have herein shown it as comprising the central ring 39 to one side of which the plate 11 is connected and to the other side of which the front plate 5 is secured, the edge of the diaphragm 4 being clamped between the front plate 5 and the body portion 39, as above stated. The back side of the casing is formed by a removable cap piece 40 which covers the projecting ends of the stem 16 and which is secured to the plate 30 11 in any suitable or appropriate way. These features of construction, however, may be varied without departing from the invention.

I find it is of advantage to make the clamping nuts 19 of such a shape that they fit tightly together, as shown, for in this way a solid wall as it were is presented back of the diaphragm 4 and the vibrations thereof are more readily transmitted to the 40 cell diaphragms.

I have shown the cell diaphragms as corrugated and this is of advantage because it tends to prevent the finely-granulated carbon 17 from caking.

45 While I have illustrated and described the cells as all connected in series, which is the arrangement that is preferable when a high voltage current is to be used, yet it would be possible to connect the cells partly in series 50 and partly in multiple if the circumstances under which the instrument is used are such as to require a current of a smaller voltage.

I have illustrated herein the preferred embodiment only of my invention and it is 55 obvious that various changes in the constructional details of the parts may be made without departing from the invention.

Having fully described my invention, what I claim as new and desire to secure by 60 Letters Patent is:—

1. In a telephone transmitter, the combination with a cell-supporting member, of a plurality of separate cells independently and adjustably supported thereby, each filled 65 with granular material and provided with

a flexible diaphragm, a main diaphragm, means separate from said supporting means for securing the flexible diaphragm of each cell independently to the main diaphragm, and means electrically connecting said cells 70 in series.

2. In a telephone transmitter, the combination with a plurality of separate cells, each filled with granular material and provided with a flexible diaphragm, of means to adjustably support each cell, a main diaphragm, means separate from said supporting means for connecting the flexible diaphragms of each cell independently to the main diaphragm, and means electrically connecting said cells in series. 75 80

3. In a telephone transmitter, the combination with a casing, of a main diaphragm secured therein, a plate sustained thereby, a plurality of separate cells each filled with granular material and having a flexible diaphragm, means connecting each flexible diaphragm to the main diaphragm, each cell having a stem extending through said plate, and springs acting on each stem on opposite 90 sides of the plate. 95

4. In a telephone transmitter, the combination with a cell-supporting member, of a plurality of separate independently adjustable cells supported thereby and insulated from each other and each filled with high resistance granular material and provided with a flexible diaphragm, a main diaphragm, means to secure the flexible diaphragm of each cell independently to the main diaphragm, and means electrically connecting said cells in series. 100

5. In a telephone transmitter, the combination with a cell-supporting plate, of a plurality of separate cells each filled with granular material and provided with a flexible diaphragm and each having a stem extending therefrom and passing through the plate, a main diaphragm, means to secure the flexible diaphragm of each cell independently to the main diaphragm, and means connecting electrically the cells in series. 105 110

6. In a telephone transmitter, the combination with a plurality of cells of insulating material each having an open end, of a pure silver flexible diaphragm closing the open end of each cell, a clamping ring screw-threaded to each cell and holding the diaphragm in place, a terminal in each cell, a granular material filling each cell, a main diaphragm connected to each of the flexible diaphragms, and an electrical connection between the clamping ring of each cell and the terminal of the next adjacent cell. 115 120 125

7. In a telephone transmitter, the combination with a main sound-receiving diaphragm, of a plurality of cells of insulating material each having an open end, a flexible diaphragm closing the end of each cell, 130

- hexagonal clamping rings screw-threaded to each cell and adapted to hold the corresponding diaphragm in place, an envelop of insulating material inclosing each clamping ring, means to support said cells with the clamping rings engaging each other, a terminal in each cell, and an electrical connection between the clamping ring of each cell and the terminal of the adjacent cell.
- 10 8. In a telephone transmitter, the combination with a casing, of a main diaphragm therein, a plate sustained by the casing, a plurality of cells within the casing each filled with granular material, a flexible diaphragm forming one side of each cell, a ter-

20 minal in each cell, each terminal having a stem extending therefrom and projecting through said plate, an electrical connection between the stem of each cell and the flexible diaphragm of the adjacent cell, and two springs on each stem, one on each side of said plate.

In testimony whereof, I have signed my name to this specification, in the presence of two subscribing witnesses.

JEROME REDDING.
